ATTORNEYS

UNITED STATES PATENT OFFICE.

JOHN E. MAUERHAN, OF OAKLAND, CALIFORNIA.

DAVENPORT.

Application filed January 24, 1921. Serial No. 439,487.

To all whom it may concern:

Be it known that I, JOHN E. MAUERHAN, a citizen of the United States, residing at Oakland, in the county of Alameda and 5 State of California, have invented certain new and useful Improvements in Davenports, of which the following is a specification.

My invention is an improved davenport, 10 the seat and back of which are hinged in such manner as to eliminate any hard places at the meeting of the seat and back when the back is swung down so that the davenport may be used as a bed.

15 Referring to the annexed drawing in which my invention is illustrated and which forms a part of this specification,

Figure 1 is a rear view of a davenport embodying my invention.

20 Figure 2 is a cross section of said davenport taken on line 2—2 of Figure 1.

Figure 3 is an enlarged rear view of one of the hinges with the rear end of the hinge slideway cut away.

25 Figure 4 is a sectional view of the hinge taken on line 4—4 of Figure 3 with hinge in the position it assumes when the back of the davenport is swung down.

In the drawing 1 is the supporting frame 30 of the davenport which is mounted on legs 2. A spring seat 3 is mounted on the frame 1, said seat comprising a cushion 4 mounted on springs 5 which rest upon the frame 1. The davenport has a back 6 which includes 35 a frame 7 and a cushion 8 mounted on springs 19 which rest upon frame 7. The back 6 is hinged at its lower outer edge to the supporting frame 1 by hinges 11. Each hinge includes a horizontal tubular slide- 40 way 12 mounted in the rear part of frame 1; a slide 13 slidable in said slideway, and a hinge member 14 hinged at one end by hinge 15 to the slide 13 and secured to the rear of the back frame 7. The slideway 12 45 is provided with a longitudinal slot 16 in its upper wall which forms longitudinal flanges 17 at the sides of said slot which engage the top of the slide 13. The knuckle 18 of hinge 15 projects through the slot 16. The 50 rear end of the slideway 12 is closed by an end wall 19 which prevents the slide 13 from pulling out of the rear end of the slideway. The end members 20 of the back frame 7 is provided with holes 21 adapted 55 to register with holes 22 in the end upright members 23 of supporting frame 1 when the

back is swung up for use as the back of the davenport. Pins 24 are inserted through the holes 21 and 22 to hold the back swung up into position for use as the back of the 60 davenport. Legs 25 are hinged to the rear of the back 6 to support the back when swung down in horizontal position.

The back 6 may be swung down rearwardly into a horizontal position to use the 65 davenport as a bed upon removing the pins 24 from the holes 21 and 22. In swinging the back down so that the davenport may be used as a bed, it first swings away from the seat 3 and supporting frame 1 on the hinges 70 15 into the position shown in dotted lines in Figure 2. The back is then pushed forwardly into the position shown in full lines in Figure 2, the hinge slides 13 sliding forwardly in the hinge slideways 12 into the position shown in Figure 4. In swinging the back up into position for use as the back of the davenport, the back is first drawn rearwardly into the position shown in dotted lines in Figure 2, the slides 13 sliding rearwardly in slideways 12 until arrested by end walls 19, and then swung upwardly on the 75 hinges 15.

The hinges 15 being located below the 80 cushions 4 and 8 of the seat and back of the davenport, are not at the meeting point of the cushions and are therefore not in position where a person may lie on them, thus 85 eliminating hard places in the meeting of the cushions of the seat and the back. 90

Having described my invention, I claim:

1. In a davenport, sliding hinges for hinging the back to the seat of the davenport, said hinges each including a horizontal slideway secured in the rear of the davenport supporting frame below the seat cushion, a slide in said slideway, and a hinge member hinged to said slide beyond the lower edge of said back and secured to the rear of the davenport back. 95

2. In a davenport, sliding hinges for hinging the back to the seat of the davenport, said hinges each including a horizontal slideway secured in the rear of the davenport supporting frame below the seat cushion, a slide in said slideway, a hinge member hinged to said slide beyond the lower edge of said back and secured to the rear of the davenport back, and means for limiting the rearward sliding movement of said slide. 100

In testimony whereof I affix my signature.

JOHN E. MAUERHAN,
